COMBINED PLAYGROUND TREE HOUSE AND SLIDE

Grant E. Jamison, Los Angeles, Calif., assignor to Jamison, Inc., Los Angeles, Calif.

Filed Apr. 29, 1971, Ser. No. 138,862

Term of patent 14 years

Int. Cl. D21—03

U.S. Cl. D34—5

FIG. 1

FIG. 5

FIG. 1 is a perspective view of one side and the front of a combined playground tree house and slide showing my new design;

FIG. 2 is an enlarged elevational view of the side of the combined playground tree house and slide opposite the side thereof illustrated in FIG. 1;

FIG. 3 is a bottom plan view;

FIG. 4 is a top plan view; and

FIG. 5 is a top plan view of the combined playground tree house and slide with the roof, slide and climbing poles and ropes, shown in FIG. 1, removed.

I claim:

The ornamental design for a combined playground tree house and slide, substantially as shown.
